(57) **CLAIM**

The ornamental design for a multi-functional CNC machine structure, as shown and described.

DESCRIPTION

FIG. 1 is a left side elevation view of a multi-functional CNC machine structure made in accordance with the subject design;

FIG. 2 is front elevation view thereof;

FIG. 3 is a top view thereof;

FIG. 4 is a bottom view thereof; and,

FIG. 5 is an isometric view thereof.

The right side elevation view is a mirror image of the left side.

The back elevation view is a mirror image of the front.
